Primary Examiner — April Rivas(74) *Attorney, Agent, or Firm* — Renner, Otto, Boisselle & Sklar, LLP(57) **CLAIM**

The ornamental design for a storage box, as shown and described.

DESCRIPTION

FIG. 1 is a top perspective view of a storage box showing our new design;

FIG. 2 is a bottom perspective view thereof;

FIG. 3 is a front view thereof;

FIG. 4 is a rear view thereof;

FIG. 5 is a right-side view thereof;

FIG. 6 is a left-side view thereof;

FIG. 7 is a top view thereof; and

FIG. 8 is a bottom view thereof; and,

FIG. 9 is an enlarged view (for magnification purposes) of a portion of the new design as indicated in FIG. 1.

The portions of the storage box shown in FIGS. 1 and 7 inside the dashed line rectangle do not form part of the claimed design.

The broken lines illustrate the bounds of the enlarged view and form no part of the claimed design.
